US0D1022730S

(12) **United States Design Patent** (10) Patent No.: **US D1,022,730 S**
(45) Date of Patent: ** Apr. 16, 2024

(54) **THERMOMETER**

(71) Applicant: **Ning Yang**, Guangdong (CN)

(72) Inventor: **Ning Yang**, Guangdong (CN)

(**) Term: **15 Years**

(21) Appl. No.: **29/920,615**

(22) Filed: **Dec. 12, 2023**

(51) LOC (14) Cl. **10-04**

(52) U.S. Cl.

USPC **D10/57**

(58) **Field of Classification Search**

USPC D10/57, 58, 60

CPC G01K 2207/06; G01K 2207/02

See application file for complete search history.

(57) **CLAIM**

The ornamental design for thermometer, as shown and described.

DESCRIPTION

FIG. 1 is a perspective view of the thermometer design showing my new design.

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a partial enlarged drawing of a portion "9" showing in FIG. 1.

The broken lines in the drawings depict portions of thermometer that form no part of the claimed design.
